UNITED STATES PATENT OFFICE.

MOSES B. DISKIN, OF NEW YORK, N. Y.

BOX-STAYING MACHINE.

Application filed January 3, 1920. Serial No. 349,243.

To all whom it may concern:

Be it known that I, MOSES B. DISKIN, a citizen of the United States, residing at New York, in the county of New York and State of New York, have invented certain new and useful Improvements in Box-Staying Machines; and I do hereby declare the following to be a full, clear, and exact description of the invention, such as will enable others skilled in the art to which it appertains to make and use the same.

The present invention relates to improvements in box staying machines, such as are employed for applying and pasting stays over the corners of boxes.

The object of the invention is the provision of a novel and improved safety device which will prevent the pressure head or die from being forcibly moved against the anvil when the operator's fingers are in position on the anvil, such as when placing the box thereon, thereby avoiding the crushing of the fingers should the machine be started too soon when placing the box on the anvil.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:

Fig. 1 is a side elevation of the improved machine.

Fig. 2 is an enlarged fragmentary view thereof showing portions in vertical section.

Fig. 3 is a front view of the parts shown in Fig. 2.

The working parts are carried by a suitable stand or frame 1, in which an anvil 2 is mounted for sliding adjustment to accommodate boxes of different sizes. This anvil 45 is adapted to receive the box 3, with one corner of the box fitted over the anvil, to receive the stay 4 thereon. This stay 4 is pressed over the corner of the box by a pressure head or die 5, which embodies the elongated body 6 of inverted V-shaped section to fit over the anvil and corner of the box.

In the present machine, the head or die 5 is carried by the lower end of a vertical slide 7 slidably engaging a main slide 8 guided for vertical sliding movement in the frame. The slide 8 is reciprocated ver-

tically by means of a drive shaft 9 mounted in the frame, a connecting rod or link 10 connecting the slide 8 and an eccentric or crank 10' of the shaft. A drive wheel 11 is mounted on the shaft 9 and a clutch 12 is used for connecting said wheel and shaft, whereby the operator may start and stop the machine at will. Thus, a clutch lever 13 which operates the clutch is connected by a rod 14 with a treadle 15 to be depressed by the foot for throwing in the clutch to start the machine.

The main slide 8 and secondary slide 7 are employed, with an automatic latch between them, whereby to provide a safety device, so that the pressure head or die 5 will only be moved downwardly against the anvil when the way is clear, whereas if the operator's fingers should be caught under the head or die on the anvil, as when placing the box thereon, the pressure of the shaft 9 will not be applied to the head or die, thus avoiding the crushing of the fingers. The latch includes a latch lever 16 carried by a pin 17 secured within the slide 8, so that said latch lever will move with the main slide, and a pair of latch pins 18 are slidable in the slide 8 and are pivotally connected to the lever 16 at opposite sides thereof. A cam 19 on the end of the shaft 9 is operable to swing the lever 16 toward the slide 7 for projecting the latch pins 18, and a spring 20 retracts the pins 18 from the slide 7. A slide 7 has sockets 21 for snugly receiving the pins 18 and below said sockets has slots or grooves 22 for also receiving said pins and permitting of vertical movement of said pins with respect to the slide 7. Coiled wire retractile springs 23 are connected to the lower ends of the slides 7 and 8, whereby to yieldingly raise the slide 7 with the slide 8, and pins or stops 24 carried by the slide 8 serve to raise the slide 7 with the slide 8 when the slide 8 reaches its uppermost position.

Figs. 2 and 3 show the slides 7 and 8 in their downward movement, with the slides latched together, thereby moving the slide 7 with the slide 8. The arrangement is such that when the slide 8 is moved to its uppermost position, whereby the pins 24 also raise the slide 7 to its uppermost position, the lever 16 is released from the cam 19, so that the spring 20 will retract the pins 18 from the slide 7, and with the sockets 21 in registration with the said pins. Then, when

the shaft 9 turns, due to the closing of the clutch 12, the slide 8 is started on its downward movement, and the cam 19 will simultaneously come into engagement with the lever 16. The slide 7 will gravitate with the slide 8, and if the downward movement of the head or die 5 is unobstructed, then the slide 7 will continue its downward movement with the sockets 21 remaining in registration with the pins 18, the slide 7 resting on the pins 24. The cam 19 will then swing the lever 16 toward the slide 7, thereby projecting the pins 18 into the sockets 21 and thereby latching the slides together, so that the die 5 will now be positively moved with the slide 8, to bring the pressure to bear on the die. The pressure head or die therefore forcibly moves downwardly and then raises up again, completing the cycle of operation, the pins 18 being withdrawn from the slide 7 when the slide 8 is raised. Should it happen that the machine is started too quickly by the operator, when the operator's fingers are still on the anvil in placing the box thereon, the head or die in moving downwardly with the slide 8 will come to rest on the fingers, thereby stopping the further downward movement of the slide 7, whereas the slide 8 continues to move on down. The arrested movement of the slide 7 will therefore result in the pins 18 moving downwardly below the sockets 21, so that when said pins are projected by the cam 19, they will enter the slots 22 instead of the sockets 21. The pins 18 will therefore merely slide downwardly and then upwardly in the slots 22 as the slide 8 continues its downward and then completes its upward movement. The head or die is therefore disconnected from the power during the emergency, to avoid the crushing of the operator's fingers, and the slide 7 will again be raised slightly with the slide 8 when the operation is completed, thereby lifting the die off of the fingers so that they can be withdrawn without injury.

In operation, when the box 3 has been placed over the anvil 2, the operator presses the treadle 15 down, to throw in the clutch 12 in order to turn the shaft 9. The other devices of the machine are driven from said shaft, for proper cooperation, and the eccentric or crank 10' of the shaft will move the rod or link 10 downwardly for depressing the die 5. When the link 10 is moved downwardly to move the slide 8 likewise, and the die 5 and slide 7 are free to move downwardly, the cam 19 in turning, during the downward movement of the slide 8, will swing the lever 16 forwardly against the tension of the spring 20, to project the latch pins 18 into the sockets 21 of the slide 7, thereby moving the slide 7 downwardly with the slide 8, and pressing the die down tight on the anvil, and then rais-

ing the slides. When the slides are raised, the cam 19 having turned, will release the lever 16 and permit the spring 20 to swing said lever away from the slide 7 to withdraw the pins 18 from the sockets 21, and the slide 7 is lifted with the slide 8 by the springs 23.

Should the operator fail to remove his or her fingers from over the anvil before the operation is started, the slide 7 is limited in its downward movement, when the slide 8 starts downwardly, by the die 5 resting on the fingers, and, as a result, the slide 8 in moving downwardly while the slide 7 is stopped, will cause the latch pins 18, when projected, to enter the slots or grooves 22 instead of the sockets 21, and said pins can move downwardly in said slots, whereby the slide 7 can remain at rest while the slide 8 is moved downwardly. This will avoid the depression of the die by power and the slide 7 will simply rest under its own weight on the fingers without injuring the fingers. In this way, when the downward movement of the slide 7 is retarded or arrested by the presence of the fingers or an obstruction between the die and anvil, the latch pins 18 instead of being projected into the sockets 21 will enter the slots 22, thus providing for an idle movement of the slide 8 without operating the die.

Having thus described the invention, what is claimed as new is:

1. In a machine of the character described, a reciprocating slide, a work performing slide, driving means for the reciprocating slide, a latch carried by one slide, the other slide having a socket for receiving the latch to advance the work performing slide with the reciprocating slide, means driven by said driving means for moving said latch into said socket to advance the work performing slide, the slide which has the socket being formed for the free movement of said latch when the work performing slide is retarded so that the latch cannot enter the socket.

2. In a machine of the character described, a reciprocating slide, a work performing slide, driving means for reciprocating the work performing slide, a latch carried by the reciprocating slide, the work performing slide having a socket for receiving said latch to advance the work performing slide with the reciprocating slide and formed for the free movement of said latch when it does not enter said socket, and means operated by said driving means for moving the latch to enter said socket so as to advance the work performing slide when it is free to move with the reciprocating slide.

3. In a machine of the character described, a shaft, a reciprocating slide operatively connected with said shaft to be reciprocated thereby, a work performing slide,

5 a latch carried by one slide, the other slide having a socket to receive the latch for advancing the work performing slide with the reciprocating slide and the slide which has 10 the socket also having a slot for the travel of said latch when it does not enter the socket, and a cam rotatable with said shaft for moving the latch to enter said socket or slot when the reciprocating slide is advanced.

15 4. In a machine of the character described, driving means, a reciprocating slide driven by said means, a work performing slide, spring means between the slides for reTRACTING the work performing slide with the reciprocating slide, a normally retracted latch carried by one slide, the other slide

having a socket for receiving said latch when projected for advancing the work performing slide with the reciprocating slide 20 and the slide which has the socket being formed for the free movement of said latch when projected so as not to enter the socket, and means driven by said driving means for projecting the latch during the advance 25 movement of the reciprocating slide.

In testimony whereof I have signed my name to this specification in the presence of two subscribing witnesses.
